4 Claims. (Cl. 93—93)

1

This invention relates to devices for automatically inserting marking strips in piles of sheets primarily intended for use by printers to facilitate the counting, in predetermined quantities, of the sheets as they fall from the printing press.

Devices for the purpose of automatically inserting strips at predetermined numbers and for counting the total number of printed sheets deposited have heretofore been proposed, but the object of the present invention is to provide a device which will cut off and automatically insert a strip of marking paper between the printed sheets after the dropping of a predetermined number of sheets and which will be reset automatically for a further cutting operation.

According to this invention the device for cutting off and inserting the strips of paper at predetermined periods comprises the provision of means for supporting a roll of paper, means for drawing said strip through the machine, means for cutting the strip into predetermined lengths, means for delivering and placing said cut lengths in the desired position comprising a fixed cutting blade and a coacting blade mounted on an arm having a vertical movement and a partial horizontal rotary movement under the influence of a spring, said means also embodying means for holding the severed strip and delivering same into the desired position in the manner herein described.

The invention further comprises means in which the movements of the feeding, cutting and delivery mechanism are effected by driving mechanism connected with the machine with which it is combined, the sequence of movements being controlled by pre-setting mechanism, said pre-setting mechanism comprises a plurality of numeral wheels furnished with means for closing a plurality of electrical contacts for the purpose of energising a pair of solenoids arranged to actuate a switch over mechanism.

In the accompanying drawings which illustrate an embodiment of this invention.

Figure 1 is a plan, partly in section on line I—I of Figure 3.

Figure 2 is a vertical transverse section on line II—II of Figure 1.

Figure 3 is a vertical longitudinal section on line III—III of Figure 2.

Figure 4 is a vertical longitudinal section on line IV—IV of Figure 2.

Figure 5 is a view drawn to an enlarged scale of a detail of construction.

Figure 6 is a plan view thereof.

2

Figures 7 and 8 are views similar to Figure 5 showing the parts in two different positions.

Figure 9 is a section on line IX—IX of Figure 4 drawn to an enlarged scale, and.

Figure 10 is a diagrammatic view of the electrical connections.

According to the embodiment of the invention illustrated in the drawings the mechanism for cutting off and inserting the strip is contained in a casing 1 formed separately from but connected to the casing 2 adapted to contain the controlling mechanism. The cutting off and inserting mechanism comprises a shaft 3 supporting a reel or drum of strip paper 4, means comprising a bar 5 carried by a pair of arms 6 pivoted at 7 in the casing 1 and drawn towards the drum 4 by a spring 8 being provided for exerting a partial restraint on the unwinding of the paper. A paper feed roller 9 is mounted on a shaft 10 and coacting therewith is a pressure roller 11 maintained in contact with the roller 9 by springs 12. The feed roller 9 is driven by a toothed wheel 13 secured on the shaft 10, the wheel 13 being arranged to mesh with a further toothed wheel 14 mounted on a driven shaft formed in two parts 15, 15^x driven from the main gear shaft 16 (Figure 4) hereafter referred to. Forward of the feed roller 11 the paper strip 4 is led between the cutting edges of a pair of knives 17 and 18 disposed between a flat table surface 19 formed on the upper surface of the casing 1 and a plate 20 disposed at a slightly higher level immediately forward of the feed roller 11. The knife 17 is secured to the rear of the table surface 19 by a bolt 21 said bolt also serving to secure the plate 20 in position. The knife 18 is secured by a screw bolt 22 to the rear surface of an arm 23 arranged to swing in a horizontal plane under the influence of spring 24^x said arm being mounted on the upper end of a vertically disposed spindle 24 arranged directly above the part 15 of the driven shaft, the lower end of said spindle 24 bearing on the surface of a resetting cam 25. The swinging arm 23 is furnished at or about the middle of its length with a pad of resilient material 26 adapted to bear on the paper strip 4 lying on the table 19. The two parts of the driven shaft 15, 15^x are interconnected by means of a clutch 27, the part 15 of the driven shaft upon which the resetting cam 25 is secured has no longitudinal or axial movement, but the part 15^x has a limited movement in and rotates with a bush 28 mounted in a fixed bearing 29. The bush 28 is provided at one end with a gear wheel 30 meshing with a pinion 31 mounted on the main gear or driving

shaft 16 connected to the drive of a printing machine by a flexible shaft or in any other suitable manner. Axial movement of the bush 28 is prevented by a collar 32 maintained in position by a set screw 33. The gear wheel 30 also meshes with a pinion 34 mounted on a spindle 35 provided with means for actuating the presetting mechanism hereafter described. The axial movement of the part 15^x of the driven shaft and thereby the engagement or disengagement of the elements of the clutch 27 is effected by an L-shaped lever pivoted to the casing at 36, the long arm 37 of which is disposed approximately horizontally, and the free end of the short arm 37^x is connected by a type of universal joint 38 to the outer end of the part 15^x of the driven shaft so that when certain conditions exist to permit the arm 37^x to be drawn by a spring 39 into an approximately vertical position, the shaft 15^x is moved axially to effect the engagement of the coacting elements of the clutch 27. The clutch elements 27, during certain periods of the operation of the device, are maintained out of engagement by a vertically disposed pin 40 having a limited sliding movement in the casing 1, the lower end of said pin resting on the free end of the long arm 37 of the L-shaped lever, the upper end bearing against the underside of, and, being pressed down by the swinging arm 23 which latter is maintained in a position at right angles to the direction of the movement of the paper strip 4 by a catch 41 controlled by a spring 42. The catch 41 is arranged to be released and the arm 23 is swung into the position shown by dotted lines in Figure 1, by a cam 43 mounted on a spindle 44 actuated by a link 45 to which movement is imparted by a lever 46 through a bar link 45^x said lever 46 being pivoted at or about its centre at 47, on the side wall of the machine, the lower end of said lever engaging with a pin 48 provided on a spindle 49 hereinafter referred to as the switch over spindle, supported in suitably disposed bearings 50, said spindle having a limited axial movement and also a limited rotative movement in both directions, a spring 51 being provided for controlling the rotative movements of said spindle and returning same to its original position. The arm 23 is returned into the operative position shown in Figures 2 and 3 by the resetting cam 25 which lifts the spindle 24 axially against the action of the spring 24^x and when the lower end of the spindle is resting on the highest point of the cam, the pin 25^x on the cam 25 strikes against the pin 24^x on the spindle 24 and turns the spindle and thereby the arm 23 through 90° in a horizontal plane against the action of the spring 24^x.

The spindle 35 actuated by the pinion 34, is provided with a boss 52 furnished with a radially disposed part 53 provided with a cam surface 53^x arranged to act on a rocker element 54 (drawn to an enlarged scale in Figures 5 to 8) secured on the switch-over spindle 49, said rocker element 54 being provided with two cam faced members 55, 56, the action of the part 53 being to effect a partial rotative movement of the switch-over spindle 49, the direction of rotation being dependent on the longitudinal position of the switch-over spindle 49, which latter is furnished with means, comprising a pin 57 coacting with a stop element 58 mounted on the casing, for limiting the degree of rotative movement in both directions.

The switch-over spindle 49 constitutes the operative member for the pre-setting drums 59, 60 and 61 which are mounted on a spindle 62 sup-

ported in bearings 63 secured in the casing 2. The pre-setting drums 59, 60, 61 comprise three figure drums, the units drum 59 is actuated in either direction by a double action ratchet mechanism hereafter described operated by the movements of the switch-over spindle 49, and is interconnected with the tens drum 60 in the known manner, and, the hundreds drum 61 is interconnected with the tens drum, by means for driving pinions 64, 65 respectively, said pinions being mounted in separate carriers 66 and 67, furnished with springs, such as 65^x and 67^x, to maintain said pinions in mesh with toothed wheels 68, 69 on the figure drums 60 and 61 respectively.

The units drum 59 is actuated in either direction from the spindle 49 through double acting mechanism comprising a pair of ratchet wheels 70, 71 formed on a drum 72 actuated by a ratchet arm 73 pivotally mounted at 74 on the outer end of an arm 75 secured on the spindle 49 (Figure 9). The arm 73 is provided with pawls 76 and 77 arranged to coact with the ratchet wheels 70 and 71 respectively by means of a vertically disposed element 78 slidably mounted on a pair of pins 79 secured in a U-shaped member 80 fixed to the casing 2. The lower end of the element 78 is furnished with a slot 81 arranged to receive a stud 82 secured in the spindle 49. The upper end of the element 78 is provided with a pair of arms 83, 84 arranged to act as retaining members for the ratchet wheels 70, 71 respectively. The pawls 76, 77 are retained in yielding engagement with the respective ratchet wheels by means of a spring 85.

The gears 59^x, 68 and 69 on the figure drums 59, 60 and 61 respectively are arranged to engage corresponding gears 86, 87 and 88 respectively on the setting drums 89, 90 and 91 which drums are so mounted on their respective spindles 92 in slotted bearings 93 (Figure 2) so that said spindles and drums may be lifted vertically by hand to disengage them for setting purposes from their coacting gears on the figure drums.

For the purpose of effecting the reversal of the direction of rotation of the figure drums 59, 60 and 61 and setting drums 89, 90 and 91 a switch-over mechanism is provided and to this end each of the figure drums 59, 60 and 61 is furnished with a radial projection 94 so arranged that when said drums come into the zero position the projections 94 make contact with projections 95 provided on electrical contacts 96 coacting with contacts 97 (more clearly illustrated in Figure 10 which diagrammatically illustrates the electrical connections) and when these coacting contacts are closed a current is completed through the battery 98 and an electro-magnet 99 which effects the axial movement of the pre-setting spindle 49, one end of which constitutes the solenoid element of the electro-magnet. Each of the setting drums 89, 90 and 91 is likewise provided with means such as a cam shaped projection 100 adapted when said setting drums are in the zero position to close a second series of contacts 101, 102 through intermediate rollers 103 formed of insulating material and thereby completes a circuit through a second electro-magnet 104 to effect the axial movement of the switch-over spindle 49 in the reverse direction.

In operation, the figure drums 59, 60 and 61 are first set to zero position and the setting drums 89, 90 and 91 to the figure at which it is desired to insert a strip, the electro-magnet 99 in circuit with the contacts 96 operates the switch-over 75 spindle 49 in one direction, the printing machine

is set in motion and when the predetermined number of sheets have been printed the swinging arm 23 which is now holding the already severed strip through the medium of the pad 26 is released from the catch 41 actuated by the solenoid 104 through the spindle 49 and swinging horizontally through 90° delivers the severed strip on top of the pile of paper situated adjacent the side wall X (Figure 1) of the casing 1. At this stage the number given on the figure drums will be that originally shown on the setting drums while the latter will have come to zero. As the arm 23 passes into the position shown in broken lines in Figure 1, the pin 40 is forced upwardly by the lever 37 under the action of spring 39 thereby re-engaging clutch 27 through shaft 15*. Shaft 15 now rotates cam 25, lifts spindle 24 and the pin 25* simultaneously strikes the pin 24* and thus effects the resetting of the arm 23 and at the same time a further length of paper-strips is fed into position and will be severed automatically from the main strip as the arm 23 again drops into its operative position. As the press continues to deposit the sheets on the pile the figure drums will be returning to zero and the setting drums will return to their original set position, and so on as the printing machine continues to operate.

What I claim is:

1. A device for automatically inserting marking strips in piles of sheets at predetermined numbers arranged to be connected to the driving mechanism of, and used in combination with, the machine for delivering the sheets it is desired to count, comprising in combination means for supporting a roll of paper in strip form, means for drawing said strip through the machine, means for cutting the strip into predetermined lengths and for holding, delivering and placing said cut lengths into the desired position comprising a fixed cutting blade, a spring-controlled arm, a cutting blade secured to said arm, means for imparting a vertical movement and a partial rotary movement to said arm, the feeding, cutting and delivery mechanism being controlled by mechanism driven by the associated machine, the sequence of movements being controlled by a pre-setting mechanism, which pre-setting mechanism comprises a switch-over spindle, a rocker element secured thereon, means actuated by the mechanism driven by said associated machine for effecting a partial rotative movement of the spindle, a stop element on said spindle for limiting the degree of rotative movement in both directions, a plurality of pre-setting interconnected figure drums, a double action ratchet device actuated by the spindle, means connecting the ratchet device with the units figure drum, a gear element on each figure drum, a second series of interconnected figure drums, a gear element on each of said figure drums arranged to mesh with the gears on the first-named figure drums, a radial projection on each of said first-named figure drums, a plurality of electrical contacts arranged to be actuated by said radial projections when the drums come into zero position to effect the closure of an electrical circuit including a battery and an electro-magnet to effect an axial movement of the pre-setting switch-over spindle, a radial projection on each of the second named figure drums, a plurality of electrical contacts arranged to be actuated by said radial projections when the drums come into zero position to effect the closure of an electric circuit through said battery and a second electro-magnet to effect an

axial movement of the pre-setting switch-over spindle in the reverse direction.

2. A device for automatically inserting marking strips in piles of sheets at predetermined numbers arranged to be connected to the driving connection with the machine delivering the sheets it is desired to count, comprising in combination a roll of paper in strip form, means actuated by the associated machine for drawing said strip intermittently through the machine, means for cutting the strip into predetermined lengths, a horizontally rotatable device carrying part of said cutting means said device also serving for holding, delivering and placing the cut lengths of strip on top of a pile of sheets delivered by the associated machine, means for resetting and repositioning said rotatable holding and delivery device into its operative position to cut a further length from said strip and hold same until a further predetermined number of sheets have been delivered by the associated machine, said resetting and positioning means being actuated and controlled by a switch-over mechanism embodying a spindle having a partial rotative movement in two directions effected by a rocker element and an axial movement in two directions imparted by a ratchet mechanism, a pre-setting mechanism for controlling the sequence of movements, and a plurality of electrical contacts actuated by said pre-setting mechanism serving to establish a circuit through a battery and electromagnets and thereby regulating the periodic delivery of the strips.

3. A device for automatically inserting marking strips in piles of sheets at predetermined numbers arranged to be connected to and used in combination with the machine for delivering the sheets it is desired to count, comprising in combination means for supporting a roll of paper in strip form, means for drawing said strip through the machine, means for cutting the strip into predetermined lengths and for holding, delivering and placing said cut lengths in the desired position comprising a fixed blade, a spring controlled arm, a catch for retaining said arm against the action of said spring in a position at right angles to the strip, a cutting blade secured to said arm arranged to coact with the fixed blade, means for releasing the catch to free the arm and enable same to move the cut lengths of paper and deliver same into the desired position, means for imparting a vertical movement and a partial horizontal rotary movement to said arm to return same to a position in which the arm is free to drop vertically and thereby enable the cutting blade carried by the said arm to coact with the fixed blade to sever a further length from the strip, the feeding, cutting and delivery mechanism being effected by the driving mechanism connected with the associated machine, the sequence of movements being controlled by pre-setting mechanism.

4. A device for automatically inserting marking strips in piles of sheets at predetermined numbers arranged to be connected to the driving mechanism of and used in combination with the machine for delivering the sheets it is desired to count, comprising in combination means for supporting a roll of paper in strip form, means for drawing said strip through the machine, a fixed cutting blade, a vertically movable cutting blade coacting therewith for cutting said strip into predetermined lengths, a spring controlled arm to the rear surface of which said vertically movable cutting blade is rigidly secured, means

for imparting a partial horizontal rotary movement to said arm for holding, delivering and placing said cut lengths into the desired position on top of the pile of sheets, and thereafter imparting a vertical movement and a partial rotary movement to said arm to bring the movable cutting blade into a position to coact with the fixed blade to sever a further length from the paper strip, control mechanism driven by the associated machine for the said feeding, cutting and delivery means and pre-setting mechanism for controlling the sequence of movements of said control mechanism.
